UNITED STATES PATENT OFFICE

156,873

SPRAYER

Virgil Elsner, Manhattan Beach, Calif., assignor
to Burgess Battery Company, Lake Zurich, Ill.,
a corporation of Delaware

Application June 14, 1949, Serial No. 3,269

Term of patent 14 years

(Cl. D62—2)

To all whom it may concern:

Be it known that I, Virgil Elsner, a citizen of the United States, residing at Manhattan Beach, in the county of Los Angeles and State of California, have invented a new, original, and ornamental Design for a Sprayer, of which the following is a specification, reference being had to the accompanying drawing, forming a part thereof.

Fig. 1 is a side elevational view of the sprayer, showing my new design;

Fig. 2 is a front elevation of the top portions shown in full lines in Fig. 1;

Fig. 3 is a top plan view of said portions;

Fig. 4 is a rear elevation, and

Fig. 5 is a bottom plan view thereof.

The dominant characteristic of my design resides in the portions shown in full lines.

I claim:

The ornamental design for a sprayer, as shown and described.

VIRGIL ELSNER.
